COMBINED TELEVISION GUIDE HOLDER AND PROGRAM REMINDER

Richard P. Bohan, 88 Edgewater Place,
Edgewater, N.J. 07020

Filed Dec. 28, 1970, Ser. No. 26,661

Term of patent 14 years

Int. Cl. D6—99

U.S. Cl. D6—184

FIG.3.

FIG.4.

FIG. 1 is a front elevational view of the combined television guide holder and program reminder, embodying the features of my new design,

FIG. 2 is a side elevational view,

FIG. 3 is a rear elevational view, and

FIG. 4 is a front perspective view thereof.

I claim:

The ornamental design for a combined television guide holder and program reminder, substantially as shown and described.
